2 SHEETS—SHEET 2.

UNITED STATES PATENT OFFICE.

THOMAS A. FLYNN, JR., OF PERTH AMBOY, NEW JERSEY.

AUTOMATIC TRAIN-STOP.

1,300,152.

Specification of Letters Patent.

Patented Apr. 8, 1919.

Application filed May 31, 1916. Serial No. 100,819.

To all whom it may concern:

Be it known that I, THOMAS A. FLYNN, Jr., a citizen of the United States, residing at Perth Amboy, in the county of Middlesex and State of New Jersey, have invented certain new and useful Improvements in Automatic Train-Stop; and I do hereby declare the following to be a full, clear, and exact description of the invention, such as will enable others skilled in the art to which it app pertains to make and use the same.

This invention relates to improvements in automatic train stopping apparatus of the type which consists of a valve positioned within the steam main which connects the boiler of a steam engine with the drive cylinders, and adapted to be closed when an attempt is made to run the train past a danger signal, the object of the invention being to simplify the operating mechanism for the valve and also to admit of the valve, when moved to closed position, being automatically locked against movement to open position.

Another object of the invention is to admit of the bleeding of the train line when the mechanism is operated to cut off the flow of steam from the boiler to the drive cylinders.

A further object of the invention is to admit of the operating mechanism being operated by a signal set at caution, as well as by a signal set at danger, or if desired to admit of the operating mechanism passing the crossing signal and operable only by the danger signal.

Other objects will appear and be better understood from that embodiment of my invention of which the following is a specification, reference being had to the accompanying drawings, forming a part thereof, in which:

Figure 1 is a detail view of a steam engine boiler, showing the operating mechanism applied thereto,

Fig. 2 is a sectional view, taken through the top of the steam boiler, and showing the steam main therein and the valve for controlling communication between the boiler and the drive cylinder,

Fig. 3 is a transverse sectional view, taken through the boiler, and showing the operating mechanism applied thereto,

Fig. 4 is a top plan view of the operating arm and the operating mechanism,

Fig. 5 is a longitudinal sectional view, taken through the outer end of the operating arm, and

Fig. 6 is a sectional view, taken through the pivoted block at the outer end of the operating arm, and showing the locking plate in operative position to prevent movement of the block.

Referring to the drawing in detail, the numeral 1 designates the boiler of a steam driven locomotive or engine, having the usual steam main 2, which connects the steam dome, to the driving cylinders, one of which only is shown and designated 3. The usual train line pipe for the air brake system is shown at 4 and is divided at a point in rear of the drive cylinder and a valve casing 5 connects the sections of the train line 4, and has a rotatable valve 6 therein, which has a passage 7 extending diametrically therethrough and which registers with the adjacent connected sections, of the train line, when the valve is in the position shown in Fig. 4, and when the valve is partially rotated the said passage 7 is adapted to register with a port 8 formed in one side of the casing 5. The valve is also provided with a radially extending passage 9, which, when the valve 6 is rotated to register the passage 7 with the port 8, registers with the rearmost pipe section of the train line and admits of bleeding of the train line.

The valve 6 is provided with a stem which has connection with one end of an operating lever 11. The opposite end of the lever 11 has connection with one end of an angular shaped link 12, the other end of the angular shaped lever being extended to provide an arm 13, which has connection with one end of an operating arm or lever 14.

The operating lever or arm 14 is carried by a depending stem 15, the upper end of which is journaled within the running board 16 on the locomotive. The lever 14 extends outwardly from the locomotive boiler and is adapted to be engaged by a suitable obstructing element, not shown, designed to be projected to different positions by a semaphore, not shown, when the said semaphore is moved to either caution or danger position, so as to rotate the valve 6 and register the passage 7 with the port 8 and the passage 9 with the train line, to admit of bleeding of the train line.

A dome 17 is carried by the locomotive

boiler and has its interior communicating with the interior of the boiler, as shown in Fig. 2. The steam main 5 is divided at a point below the dome 17 and has a valve casing 18 fitted therewith connecting the adjacent sections. The valve casing 18 has its interior provided with a partition wall 19, the upper end of which is arranged in spaced relation with the inner surface of the valve casing to provide ports 20 and 21, located, respectively, on opposite sides of the partition 19. The port 20 is adapted to be closed by a valve 22, which is carried by a stem 23 operable through an angularly disposed sleeve 24 carried by the valve casing 18. The sleeve 24 extends into the interior of the dome 17, and has its upper end provided with a flange 25, which has connection with a flange 26 carried by the lower end of another angularly disposed sleeve 27, by means of bolts 28. The upper end of the sleeve 27 extends through the top of the dome and the upper end of the stem extends through the sleeve 27 and has its terminal 25 extending beyond the upper end of the sleeve and connected to one end of a lever 29. A cap 30 is carried by the upper end of the sleeve 27 and has a passage therein for the passage of the stem and a suitable packing 30 is dispensed within the cap and around the adjacent portion of the stem and is adapted to prevent leakage.

The lever 29 is pivoted, at a point intermediate its ends, to an angularly disposed 35 supporting member 31, which is secured to the top of the dome 17, and the lever 29 has that end opposite the one which has connection with the stem 23, pivotally connected to the upper end of a vertically disposed link 40 32. The link 32 is curved outwardly and downwardly from the upper end and extended along the adjacent side of the boiler and through an opening in the running board 16. The lower end of the link is bifurcated and 45 connected to an arm of a bell crank lever 33, the said bell crank lever being carried by a depending bracket arm 34, carried by the under side of the running board 16 and the other end of the bell crank lever is pivotally connected to one end of a substantially S-shaped lever 35, the other end of the lever 35 being pivotally connected with the inner end of the operating arm 14.

In use, when the arm 14 engages the obstructing element set by the semaphore, the arm 14 will be given a partial rotation so as to effect registration between the passage 7 in valve 6 and the port 8 in the casing 5, and between the passage 9 in the valve on 55 the train line, so as to admit of the bleeding of the train line. When the arm 14 is thus operated, the bell crank lever 33 will be simultaneously operated to effect raising of the link 32 and the rocking of the adjacent 60 end of the lever 29 upwardly, resulting in

the valve stem 23 being moved downwardly and seat the valve so as to close the port 20 and cut off the supply of steam to the cylinder 3. The valve stem 23 is provided with a series of rack teeth 36, and the supporting 70 element 31 carries a pawl 37 adapted to interchangeably engage the rack teeth when the stem 23 is moved downwardly, so as to lock the valve in closed position. The outer end of the arm 14 is provided with an enlarged portion 38, to which is hingedly connected a block 39. When it is desired to operate the arm so as to apply the brakes and cut off the supply of steam to the cylinders, when the signal is set at caution, the block 80 39 is moved to the position shown in Fig. 3 so as to admit of the obstructing element, which has been projected to the desired position by the semaphore, engaging the block to effect movement of the arm. When it is 85 desired to only operate the arm when the signal is set at danger, the block 39 is folded on the forward side of the enlarged portion 38 of the arm 14, so as to lie out of the path of the obstructing element when set at caution. The enlarged portion 38 and the block 90 39 are provided with recesses adapted to register when the block 39 is in operative position, and to removably receive a locking plate 40 for holding the block in said operative position, the plate 40 being provided with an eye 41 for the insertion of a suitable tool for facilitating the removal of the plate when it is desired to fold the block on the 95 enlarged portion 38 of the arm 14. 100

While I have herein shown and described one preferred form of my invention by way of illustration, it is to be understood that variations may be made within the scope of the claims, without departing from the spirit 105 of the invention.

What is claimed, is:

1. In an automatic train stop, the combination with the steam main of a steam engine having a cut off valve therein, a train line pipe carried by the engine and having a discharge port therein and a valve for normally closing the port, of an outwardly projecting operating lever, means for connecting the operating lever to the valve in the 11 air pipe for operating the valve for opening the port when the valve is operated, means for connecting the lever to the valve in the steam main for moving the valve to closed position when the lever is operated, a horizontally swinging block hingedly connected to the free end of the operating lever, and means for holding the block in an extended position, for the purpose specified. 115

2. In an automatic train stop, the combination with the steam main of a steam engine having a cut off valve therein, a train line pipe carried by the engine and having a discharge port therein, and a valve for normally closing the port, of an outwardly pro- 12

jecting operating lever pivoted intermediate its ends, a link connecting the inner end of the operating lever to the valve in the train line pipe for operating the same for opening 5 the port, a bell crank pivoted at its angle, a link connecting the inner end of the operating lever with the adjacent end of the bell crank, and a rod connecting the opposite end of the bell crank to the valve of the

steam main for moving the valve to closed 10 position when the lever is operated.

In testimony whereof I affix my signature in presence of two witnesses.

THOMAS A. FLYNN, JR.
